US00D926809S

(12) **United States Design Patent** (10) **Patent No.:** **US D926,809 S**
Murphy et al. (45) **Date of Patent:** **** Aug. 3, 2021**

- (54) **DISPLAY SCREEN OR PORTION THEREOF WITH A GRAPHICAL USER INTERFACE**
- (71) Applicant: **REliaQUEST HOLDINGS, LLC**, Tampa, FL (US)
- (72) Inventors: **Brian P. Murphy**, Tampa, FL (US); **Joe Partlow**, Tampa, FL (US); **Colin O'Connor**, Tampa, FL (US); **Jason Pfeiffer**, Tampa, FL (US)
- (73) Assignee: **ReliaQuest Holdings, LLC**, Tampa, FL (US)
- (**) Term: **15 Years**
- (21) Appl. No.: **29/693,794**
- (22) Filed: **Jun. 5, 2019**
- (51) **LOC (13) Cl.** **14-04**
- (52) **U.S. Cl.** **USPC** **D14/488**
- (58) **Field of Classification Search**
 USPC D14/485-495; D20/11; D21/324, 325

Primary Examiner — John M Otte(74) *Attorney, Agent, or Firm* — Brian J. Colandreo; Jeffery T. Placker; Holland & Knight LLP(57) **CLAIM**

The ornamental design for a display screen or portion thereof with a graphical user interface, as shown and described.

DESCRIPTION

The FIGURE is a front view of a display screen or portion thereof with a graphical user interface showing the claimed design.

The broken lines are included for the purpose of illustrating portions of the display screen or portion thereof with a graphical user interface that form no part of the claimed design.

1 Claim, 1 Drawing Sheet
